UNITED STATES PATENT OFFICE.

JOHANN MARTINEK, OF VIERNSEN, GERMANY.

THREAD-CUTTING DEVICE FOR AUTOMATIC WEFT-REPLENISHING LOOMS.

972,118.

Specification of Letters Patent.

Patented Oct. 4, 1910.

Application filed May 10, 1909. Serial No. 495,006.

To all whom it may concern:

Be it known that I, JOHANN MARTINEK, a subject of the Emperor of Germany, residing at 30 Klöratherstrasse, in the town of 5 Viersen, Rhine Province, Prussia, in the German Empire, have invented certain new and useful Improvements in Thread-Cutting Devices for Automatic Weft-Replenishing Looms, of which the following is a 10 specification.

The hitherto known devices for severing the ends of weft thread from the selvage of the fabric in the looms, are of two kinds: (1) Shears, having one stationary and one 15 movable cutting blade, constantly working along the selvage of the fabric, for instance such as described in the American specifications Nos. 585,465 and 822,169/1906. (2) Devices having hooks which catch the filling 20 ends and bring them in or against the cutting arrangement. Such devices are described in the American specifications Nos. 630,236/1899, 640,656/1900, 704,715/1902 and 801,223/1905.

The first-mentioned devices are unsatisfactory inasmuch as they are quickly worn out and therefore must often be renewed, besides, as they must be kept as some distance from the selvage, they do not for certain 25 prevent the thread ends from being caught in the cloth. The second-mentioned devices, of which there are many modifications in the market, have not been successful either, in that they are generally complicated and 30 expensive of production and do not insure an even and certain removal of the thread ends. The hooks are not always reliable, and even when the thread ends are properly 35 caught by them, they are often dropped again before coming into contact with the cutting blades. On the other hand, when 40 the thread ends are brought against the cutting blades, they are often caught between the latter instead of being cut off and are then torn away through the movement 45 of the fabric. Even when the hooks are quite new, and thus more reliable, the thread ends are only cut off at a certain distance from the selvage which therefore, at all 50 events, is not made perfectly even. Most looms, therefore, are worked without cutting device.

The present invention relates to a cutting device which, while cutting the thread ends 55 close to the edge of the fabric, acts imme-

dately before the lay returns and the next shot of the shuttle takes place. It only works at each change of pirn and is therefore correspondingly durable and it is absolutely reliable in its function.

In the annexed drawings, the invention is 60 illustrated, Figure 1 representing the device in resting, and Fig. 2, in working position. Fig. 3 is a plan of the device. Fig. 4 shows the cutting blades closed and withdrawn, and Fig. 5, the same open for working.

The device consists of an arm *a*, a casing *b* rigidly connected to the same, and a base-plate *c*, of which the latter is suitably arranged on the temple stand of an automatic loom. The arm *a* is slidably connected to the base-plate *c* and controlled by a spring *a'*, so that, in the event of any miscarrying of the shuttle, the temple can yield together 70 with the base-plate, without inflicting any injury to the device or to the reed. In the casing *b*, which at both ends is provided with slots, a slide *d* is mounted. Said slide is provided with serrations on its upper edge 75 and is forced by a spring *e* as far to the left as a slot *d'* and a pin *d''*, guided in same, will allow. At the side of the slide *d*, a locking lever *f* is arranged, which is provided with two pins *f'* and *f''*, of which the 80 former serves as a detent for the slide *d*, whereas the latter alternately stops and releases an actuating lever *g* connected to the shears. The lever *g*, which with one end is pivoted to one of the cutting blades, is at the 85 opposite end provided with a pin *g'* engaging with the serrations of the slide *d*. It is further provided with a catch *g''* adapted to contact with the pin *f'* of the lever *f*. The shears consist of two cutting blades *h* 90 and *i*, pivotally connected at *j*. The blade *h* is provided with an arm *h'* which is pivoted to the lever *g*, and the arrangement is such that when said arm *h'* is actuated in the position shown in Fig. 5, the blades are first 95 closed on one another and thereupon withdrawn, entirely or nearly so, into the slot of the arm *a* where they are slidably mounted. This position is shown in Fig. 4. A strong spring *k* presses the shears out of the slot in 100 open position, as soon as the rest of the mechanism allows it to do so. A spring *l*, arranged in the casing, is adapted to press the levers *f* and *g* downward. Finally, a starting lever *m* is provided which contacts 105 110

with the lever *f* and coöperates with the replenishing mechanism of the loom in such a manner that it assumes the position shown in Fig. 2 for every change of pirn.

5 The working of the device is as follows:— In the position shown in Fig. 1, the shears are closed and withdrawn into the slot of the arm *a*. The lever *g* is held by the pin *f''*, and the slide *d* by the pin *f'* of the lever 10 *f*. When the replenishing mechanism is put into operation, it actuates the lever *m* so that it presses the engaging arm of the lever *f* downward, thereby raising the opposite arm and with it the pins *f'* and *f''*, so as to 15 release the slide *d* and the lever *g*. The former is then forced out by the spring *e* and the latter, together with the cutting blades *h* and *i*, moved by the spring *k* into the position shown in Fig. 2. The replenishing mechanism having performed its service, the lever *m* returns to its initial position. The arm *h'* of the blade *h* is now within the reach of the lay of the loom, by each stroke 20 of which said arm, and with it the shears, are moved back into the position shown in 25 Fig. 4. At each such movement the shears first cut off the thread ends from the selvage and then retire into their slot so as not to come into contact with and damage the reed. 30 Following the movements of the arm *h'*, the lever *g* each time returns the slide *d* one tooth space, by means of the pin *g'*. The slide *d* cannot partake in the return movements of the lever *g*, as it is held back by the 35 pin *f'*. The operation of the shears thus continues until the pin *f'* has passed the last serration of the slide *d*, when the lever *f* descends and arrests the lever *g* by means of the pin *f''*. The device now remains at 40 rest until it is again set in operation by the replenishing mechanism.

I claim:—

1. An automatic cutting device for automatic weft-replenishing looms, comprising 45 a base plate mounted on the temple stand, an arm and a casing slidably mounted on said base plate, pivotally connected cutting blades slidably arranged in a slot in said arm and adapted to cut the thread ends 50 close to the selvage of the fabric, an arm on one of said blades adapted to be actuated by the lay of the loom when the device is in operative position so as to close the blades for cutting the thread and thereupon to 55 withdraw them into the slot, means for retaining the cutting blades in the slot in inoperative position after a pre-determined number of cutting operations, and means for releasing the blades through the action 60 of the replenishing mechanism, substantially as set forth.

2. An automatic cutting device for automatic weft-replenishing looms, comprising 65 a casing mounted with a base plate on a temple stand, an arm connected to said cas-

ing, cutting blades actuated by the lay slidably arranged in a slot in said arm and adapted to cut the thread ends from the selvage of the fabric and then to withdraw into said slot, a spring tending to hold said cutting blades in operative position, an actuating lever mounted in said casing and pivoted to one of said blades, a spring-actuated slide, provided on its upper edge with serrations, arranged at the side of said lever, a 70 pin on said lever adapted to engage with the serrations of said slide so as to move it the space of a serration, against the action of its spring, for each reciprocating movement with the cutting blades, means for locking 75 said slide and said lever in inoperative position when the slide has been sufficiently advanced by the lever, and means for putting the device into operation through the action of the replenishing mechanism, substantially 80 as set forth.

3. An automatic cutting device for automatic weft-replenishing looms, comprising a casing mounted with a base plate on a temple stand, an arm connected to said casing, pivotally connected cutting blades arranged in a slot in said arm and adapted to cut the thread ends from the selvage of the fabric and then withdraw into said slot through the action of the lay, a spring 90 adapted to open and to advance said cutting blades when the lay moves back, an actuating lever arranged in said casing and connected to one of said cutting blades so as to follow their movements and thereby to advance a spring-actuated slide mounted at its side, a double-armed locking lever pivoted at the other side of said slide, pins on one arm of said lever, one adapted to lock 95 said slide when the latter has been sufficiently advanced by the actuating lever, and the other to lock the actuating lever and thereby the cutting blades in inoperative position, a spring controlling the vertical movements of said levers, and a starting 100 lever coöperating with the replenishing mechanism and engaging with said locking lever so as to release said slide and said actuating lever with the cutting blades when the replenishing mechanism is operated, 105 substantially as set forth.

4. An automatic cutting device for automatic weft-replenishing looms, comprising a casing mounted with a base plate on the temple stand, pivotally connected cutting blades arranged in an arm on said casing and held in cutting position by a spring and adapted to be actuated by the lay so as to close for the purpose of cutting the thread ends and then to withdraw into a slot in said arm, an actuating lever connected to one of said cutting blades and adapted to advance a spring-actuated slide provided with serrations through the space 110 of a serration for each movement, a lever 115

adapted to lock said slide and said actuating lever when the pin on said locking lever has passed the last serration of said slide, and a starting lever coöperating with the replenishing mechanism and engaging with said locking lever so that the cutting device is put into temporary operation as

soon as the said replenishing mechanism is actuated, substantially as set forth.

JOHANN MARTINEK.
